BYRON E. ELDRED, OF KENSINGTON, NEW YORK.

METHOD FOR AIDING AUDITION.

Application filed December 10, 1924. Serial No. 755,077.

My invention consists in a method and apparatus for aiding the audition of persons of defective hearing.

The method consists in producing and emitting into the surrounding space a continuous and sustained succession of rythmical air waves of sufficient pitch and amplitude whereby the ears of persons of defective hearing are rendered more sensitive to normal sounds. Such waves are hereinafter referred to as "sensitizing waves".

My method is useful not only in enabling more or less deaf persons to intelligibly hear sounds or speech of normal intensity while they are within the influence of such waves, but also for improving the audition of some classes of deaf persons, by repeated subjection to the influence of such sensitizing waves.

While I find that in most cases of defective audition the sensitizing wave may be applied to the best advantage at a certain pitch and amplitude to suit the special case of deafness, and this pitch and amplitude may be readily determined by experiment for an individual case, I also find that greatly improved hearing results in most cases by waves of inaudible frequencies and substantial magnitude. Such waves I propose for general use in theatres, churches, auditoriums, homes and the like, and it will be obvious to a person skilled in the art that the amplitude of the wave so employed should be adjusted to suit the dimensions and general interior design of the auditorium.

In improving the acoustic properties of auditoriums, theatres, churches and the like for the reception of sound by persons of defective hearing, I find that sensitizing waves in frequency and amplitude predetermined for a suitable sensitizing effect for average persons of defective hearing are effective. These waves have a healthy natural effect upon the abnormal ear which is probably brought about by effecting a responsiveness of the tensor tympani muscle. This tensing effect upon the relaxed vibratory system of the deaf ear is practically entirely without effect upon the normal healthy ear.

I do not, however, wish to limit myself to the use of inaudible frequencies in the carrying out of my invention—as certain audible frequencies, especially those approaching the limits of audibility, will be found to be quite satisfactory—but waves of low

or inaudible frequencies are preferable because they avoid any possible annoyance to people of normal hearing.

In practice of my invention I use not only waves of actually inaudible frequencies, i. e. 60 of frequencies either above or below the limits of audition, but also waves approaching these limits and of such frequency, if audible to be unobjectionable to persons of normal hearing. The limits of audition are 65 not capable of exact delimitation as they vary widely in persons of normal hearing.

Perhaps the limits of useful tone may be roughly placed between 60 and 5000 double vibrations per second, although the authorities differ widely as to these limits.

I find that it is desirable to use a wave which has little or no tonal quality for the human ear because such a wave effects little or no auditory nerve response and for that 75 reason may be applied with the desired strength or amplitude without causing nerve fatigue, or ear discomfort, especially to persons of normal hearing.

In the practice of my invention, the adjustment of amplitude is apparently more important than the adjustment of frequencies of vibration. I find that too great an amplitude may operate to defeat the purposes of the invention and that deaf persons within the influence of sensitizing waves of too great amplitude may not hear, and may experience uncomfortable sensations. In some special cases, particularly in children, it will be found necessary to use vibrations of high frequency.

In either case, the essential condition is that there is produced a forceful action by the air waves on the mechanism of the ear. With waves of low frequency, the amplitude 80 of the waves is made sufficient to adequately affect the ear mechanism, while with waves of high frequency the effect of the very rapidly repeated application of the smaller amplitude waves exerts such force on the ear 100 mechanism as to produce the desired effect. There is no practical difficulty in properly adjusting the amplitude of the waves, since the wave-producing mechanism may be adjusted to the proper degree, or the listener 105 may vary his distance from the wave-producing apparatus.

It is well known that deaf people who can be made to hear at all require sound waves of excessive amplitude (i. e. very loud 110

talking) to overcome their defective audition. I have found that sensitizing waves of sub-audible or super-audible frequencies serve the same purpose as supplying excessive amplitude to the sound waves of the sound communication to be imparted. And the relief effected by my invention is thus two-fold in that in voice communication it saves the effort of very loud talking by the person who is endeavoring to communicate with the person of defective audition.

The sensitizing waves used in this manner while preferably of pure form, need not be so free from what may be termed staccato components nor of as great amplitude as when a more lasting effect on the hearing is to be produced. In this latter case the waves should be of substantially pure form, that is containing a dominant percentage of a fundamental note not compounded with waves of different frequencies.

I do not wish to be limited to any special type of apparatus or device for carrying out my invention. I have shown and described diagrammatically two types of apparatus which I have found suitable: Fig. 1 shows an apparatus for the generation of low frequency sensitizing waves; Fig. 2 shows an apparatus for the generation of high frequency sensitizing waves.

Referring to Fig. 1, M is a motor having a rheostat R_3 in its field circuit to control the speed of the motor. N is a self-excited alternating current generator having a commutator N_1 from which direct current is delivered to the field magnet coils N_2 , and through wires 20, 21 to the coil L_4 surrounding one limb I_3 of the magnet I. Collector rings N_3 on the generator shaft deliver alternating current through wires 22, 23, to coil L_3 , this circuit including a resistance R_4 . The coil L_3 consists of only a few turns, is light in weight and wound around the tubular end of a cone-shaped diaphragm D of light fibrous material, such as paper or parchment, which is carried by a thin rubber ring F secured to the edge of a circular opening in the baffle plate B. The diaphragm is thus free to move in the direction of its axis. The coil L_3 is located in the magnetic field between the poles I_1 , I_2 of the magnet I, the end of the core I_3 extending into the coil L_3 . Due to the oscillations of the alternating current, a magnetic field will be set up in L_3 which will change its direction with each change in direction of the oscillating current. When this magnetic field is in the same direction as that due to magnet I, the two fields will act to attract each other, thereby causing coil L_3 to move along its axis from its normal position. When the magnetic field of L_3 reverses its direction a repelling action will take place and the coil L_3 will move in the other direction. In this manner the dia-

phragm D is thrust back and forth in exact synchronism with the electric oscillations, and air vibrations or waves of regulated pitch and amplitude are produced and sent out. The baffle plate B prevents the air from circulating around its edges, and the waves or vibrations are thus outwardly directed. The frequency of the waves may be controlled by rheostat R_3 and the amplitude may be varied by rheostat R_4 .

For producing high frequency air waves, I may use the device shown in Fig. 2. The wave generator is of the same construction as that described in Fig. 1, the unidirectional and oscillating currents delivered to the coils L_4 and L_3 being furnished however from an alternating current rectifier and an oscillator of the vacuum tube audion type.

Referring to Fig. 2, 24 and 25 are the usual alternating current supply mains and are connected to the primary coil T_1 of a transformer which has three other coils on the same iron core T. Coil T_2 has many more turns than the primary and operates as a step-up transformer generating a high voltage difference at its terminals. Each terminal is connected to the anode or plate of thermionic rectifiers R_1 and R_2 , which permit current to flow in one direction only, viz, from plate to filament. Current to heat the filaments of the rectifier tubes is furnished from a third coil T_3 , wound with a sufficient number of turns to produce an induced voltage of proper amount. The center of the coil T_3 will have no voltage variations, and at this point is one terminal of the circuit including the coil L_4 of the wave generator.

Due to the alternate positive and negative variations impressed on the plates of the rectifier tubes, each tube will alternately pass the current through to its filament thereby causing a high voltage to be impressed upon the terminals of coil T_3 . By connecting the center point of the coil a nearly constant voltage is available which is practically equal to half the voltage at the terminals of coil T_2 . It is this constant voltage that operates the oscillator to be later described. The coil T_4 supplies current for the filament of the three-element vacuum tube O.

The oscillator unit is the generator of high frequency currents which are later converted into sound waves at the pitch and amplitude required for the purpose of the invention. The operation is exactly the same as that of any vacuum tube audion oscillator and consists in supplying the three-element vacuum tube O with a high voltage to its anode through the coil L_2 . A magnetic field will be set up in this coil due to the anode current and will react in coil L_1 to induce a voltage in it. This voltage will

be impressed upon the grid of the vacuum tube and, as the potential of the grid controls the passage of current in the anode circuit, it will be apparent that steady oscillations will be generated in the coils L_1 and L_2 and condensers C-1 to C-7, the periodicity of these oscillations depending upon the values of these parts. In order to isolate the grid from the high voltage of the anode circuit the condenser C-8 is provided. The capacity of this condenser is very large and therefore its reactance to the oscillating current is very low at high frequencies, but it has infinite reactance to the direct current of the anode circuit. Switches are provided to connect in the proper condensers for any frequency. It will be noted that the coil L_1 does not connect directly to condenser C-8 as does coil L_2 but connects through the coil L_3 in the wave generator and thence back to C-8. By this means the oscillating current passes through L_3 as it is a part of the oscillating circuit.

At each end of the coil L_4 condensers C_9 and C_{10} of proper value are connected whose other terminals connect to the point of zero potential of coil T_2 . These condensers operate in conjunction with L_4 to suppress any undesirable irregularities in the anode current from the alternating current converter and thereby cause other vibrations than those desired to be heard when the set is in operation.

When the switch S is closed the alternating current in coil T_1 sets up a varying magnetic field in the core T and the secondaries will each have induced in them voltages depending upon the number of turns. Alternating current from coil T_2 will pass through the rectifiers R_1 and R_2 . The filaments will be heated by a current flowing from T_3 . The oscillator filament is heated from coil T_4 . The rectified alternating current will then flow from the center of coil T_3 through L_4 thereby energizing magnet I and thence through oscillator coil L_2 to the vacuum tube O and back to T_2 through the common connector between coils T_4 and T_2 . The oscillations in L_1 , L_2 and L_3 and the condensers C-1 to C-7 are thus established. Due to these oscillations a magnetic field will be set up in L_3 which will change its direction with each change in direction of the oscillating current.

The diaphragm D will therefore be oscillated in the manner previously described to produce air waves of any required high frequency.

Each of these devices will produce rhythmic waves which produce the effect of sinusoidal waves in that they contain a sufficiently large percentage of the predetermined fundamental. Sound waves in air are a series of condensations and rarefactions or variations in pressure, and these

variations in pressure operate upon the ear drum and its accompanying mechanism to cause the sensation of sound.

The arrangement shown in Figs. 1 and 2 may be used either for the correction of defective audition while the person is within the influence of the sensitizing wave or for therapeutic application to correct defective audition through extended treatment. For the first purpose relatively low energy, such as of the order of five or ten watts, is used, while for the second purpose much higher powers, as for example two to three hundred watts, may be needed.

It is quite practicable to employ vacuum tube circuits for the generation of low frequency oscillations, but the apparatus is more complicated and cumbersome due to the necessity of using large values of inductance and capacity.

I believe I am the first to propose the correction of defective audition by means of a device which conditions a deaf ear to respond to sounds which are heard by the normal ear and not otherwise heard intelligibly by the defective ear. My invention concerns conditioning the defective ear for hearing by pervading a region in which the hearer is located with practically unnoticeable waves of predetermined frequency and amplitude, which I have proven to be effective for this purpose. All other means disclosed in the art employ devices for conditioning the sound waves for reception by the defective ear either through volume collection or amplification of the original sound. According to my invention, instead of magnifying the sounds to be heard, I improve the sensitiveness of the receiver, that is to say, the receiving ear mechanism. In practice of my invention, by means of a suitable device I cause to be freely emitted into space about the person of defective hearing the sensitizing waves. The volume of space sensitized for correcting audition will of course depend somewhat upon the size of the diaphragm or other suitable device employed to produce air waves, likewise the amplitude of the wave as generated will affect the distance of its useful employment. I find however that the waves generated by the apparatus I have described herein are effective over a very considerable area. A diaphragm of twelve inches or less will sensitize under proper conditions of application, the largest auditorium, and a six inch diaphragm has served satisfactorily at a distance of thirty feet out of doors.

It is well known that many persons of defective hearing can hear loud sounds. Based upon this fact various devices have been constructed to aid audition, comprising in principle sound collecting devices such as ear trumpets and sound amplifying devices on the principle of the telephone transmitter

and receiver. Such devices present many disadvantages in use which it is unnecessary to enumerate.

It is also known that some forms of deafness are relieved in the presence of certain noise conditions, for example some persons of defective hearing unable to hear normal tone speech under ordinary conditions, can while riding on a railroad train hear apparently better than persons of normal audition under like conditions.

Under such circumstances, the deaf person hears because the amplitude of the noise vibrations is greater than that of the normal or ordinary voice vibrations which the deaf person can not hear. Similarly, according to my invention, the amplitude of the substantially noiseless vibrations produced is greater than those which would occur in normally audible sounds, and accordingly the ear mechanism of the person hard of hearing is subjected to pressure variations greater than those occurring in normally audible sounds.

I have established the fact that the necessary condition to make deaf ears responsive is amplitude of air wave vibration, and that it is not necessary to accomplish this with a wave which creates a noise or even an audible sound.

While I have described particular forms of apparatus which have been developed by long experiment and have been found to be suitable for the purposes of my invention,

it is to be understood that other forms of apparatus which operate in a similar way to produce similar results are within the scope of my invention.

As a continuation in part of this application I have filed application Ser. No. 40204,148, July 7, 1927.

I claim:

1. A method of improving the acoustics or audibility qualities of a predetermined space for persons of difficult hearing therein, which method consists in maintaining in the atmosphere of said space a continuous succession of rhythmical air waves of such amplitude as to cause pressure variations greater than those occurring in normal unamplified sounds, the said waves having a frequency adjacent the marginal frequency of the audible range. 45

2. A method of improving the acoustics or audibility qualities of a predetermined space for persons of defective hearing therein which method consists in maintaining in the atmosphere of said space a continuous and sustained succession of air waves of such force producing characteristics as to cause pressure variations greater than those occurring in normally audible sounds, the said waves being of such frequency as to be substantially inaudible. 55

In testimony whereof, I affix my signature. 60
